UNITED STATES PATENT OFFICE

2,672,388

CLOTHESBAG HOLDER

Latino V. Sinson, Oak Park, Ill.

Application September 11, 1951, Serial No. 246,055

1 Claim. (Cl. 312—6)

1

This invention relates to a clothes bag holder and has for its primary object to suspend a clothes bag in a rolled condition when it is not in use and thereby to save storage space.

Another object is to suspend the clothes bag in such a manner that it may be instantaneously moved to an unrolled position and opened for the introduction of an article of clothing thereinto.

A still further object is to protect the upper end of the clothes bag and a garment suspended therein from the collection of dust and dirt and to deflect any dust that may settle downwardly from the upper end of the clothes bag and a garment suspended therein.

The above and other objects may be attained by employing this invention which embodies among its features an elongated substantially transversely inverted U-shaped hood, a spring actuated roller carried by the hood within the confines thereof, a clothes bag of flexible material connected to the roller and adapted to be rolled thereon by the effort of the spring, means carried by the hood to support the holder in suspended position with relation to a support and means carried by the roller and accessible from the exterior of the hood for holding said roller against movement under the influence of the spring when the clothes bag is extended.

Other features include a rod carried by the roller, means carried by the front wall of the clothes bag adjacent the upper end thereof to slidably suspend said front wall on the rod and said front wall having a slit opening through the upper edge thereof and extending downwardly substantially midway between opposite sides of the clothes bag to provide an access opening by which articles of clothing may be introduced into or removed from the clothes bag, and a slide fastener carried by the front wall of the clothes bag for closing said slit.

In the drawings,

Figure 1 is the front view in elevation of a clothes bag holder and clothes bag embodying the features of this invention.

Fig. 2 is an edge view thereof,

Fig. 3 is a fragmentary longitudinal sectional view through the hood showing the front of the clothes bag suspended on the rod, and

Fig. 4 is a transverse sectional view on an enlarged scale taken substantially along the line 4—4 of Fig. 3.

Referring to the drawings in detail a hood 10 formed of a suitable rigid material is of substantially inverted U-shaped cross section and has opposite ends closed by end walls 12. A suitable

2

hanger member 14 is attached at opposite ends to the hood 10 adjacent opposite ends thereof and extends upwardly therefrom and is provided with a hook 16 which may be engaged with any suitable support for suspending the hood and clothes bag in an elevated position.

Mounted for rotation within the hood 10 is a roller 18 of the type conventionally used for supporting window shades, and this roller is equipped adjacent one end with a longitudinal recess 20 containing conventional coiled spring 22, one end of which is anchored to the interior of the roller while the opposite end is connected to a suitable pintle 24 which is anchored in one of the end walls 12 and held against rotation relative to the hood 10. The opposite end of the roller is provided with an axially extending stub shaft 26 which projects through the end wall 12 opposite that receiving the pintle 24 and carries adjacent its outer end a notched drum 28. A spring pressed pawl 30 is pivotally connected to the wall 12 adjacent the drum 28 and is adapted to engage in a notch in said drum in order to hold the roller 18 against rotation by the effort of the spring 22.

Carried by the roller and extending longitudinally adjacent the side thereof is a bar 32, and fixed to the roller diametrically opposite the bar is the back wall 34 of a garment bag designated generally 36. A front wall 38 of the garment bag 36 is connected to the side and bottom edges of the back wall by conventional gussets 40, and the front wall is provided with a vertically extending slit 42 which extends through the upper edge thereof substantially midway between opposite side edges of said front wall. Suitable slide members 44 are mounted on the rod 32 and attached to the upper edge of the front wall 38 of the garment bag 36 which is preferably notched as at 46 to enable the opposite panels of the front wall defined by the side edges thereof and the slit 42 to slide longitudinally on the rod to render the interior of the garment bag accessible for the introduction thereto or removal of garments therefrom. A suitable slide fastener 48 is carried

45 by the front wall of the garment bag and in one position closes the slit 42 while in its opposite extreme position opens the slit so that the panels of the front wall 38 defined between the slit 42 and the opposite side edges of said front wall may be moved longitudinally along the bar 32 to open or close the access opening.

Carried by the roller 18 substantially midway between opposite ends thereof and extending into the upper open end of the garment bag 36 is a 55 relatively shallow loop 50 which when the gar-

ment bag is extended may support a conventional garment hanger 52 within said garment bag and upon which a garment may be supported.

In use with the parts extended as illustrated in Fig. 1, it is obvious that upon moving the slide fastener 48 to its uppermost extreme, a garment supported on the hanger 52 will be protected against injury through the deposit of dust or dirt thereon as any dust or dirt settling downwardly will contact the hood 10 and be deflected down opposite sides of the garment bag 36. When it is desired to store the garment bag, the garment and hanger 52 are removed from their position within the garment bag by disengaging the hook of the hanger from the loop 50 and opening the slide fastener to its fullest extent. With the garment and hanger thus removed, the slide fastener 48 is moved upwardly so as to close the slit 42, and upon lifting the pawl 30 out of the notch in the drum 58, the spring 22 will cause the roller to rotate about its longitudinal axis and wind the garment bag about said roller and within the confines of the hood 10. Owing to the shallowness of the loop 50 any obstruction caused by its protrusion beyond the surface of the roller will be insufficient to in any way affect the device. When it is again desired to use the garment bag all that is necessary is to exert downward pull on the bottom edge thereof so as to unwind it from the roller 18 against the effort of the spring 22 which as the unwinding of the garment bag takes place becomes loaded ready for a repeat operation in rolling the garment bag into the hood. Upon unwinding the garment bag to its fullest extent, the pawl 30 will engage in a notch in the drum 28 and hold the roller 18 against rotation. Upon moving the slide fastener 48 downwardly to its fullest extent, the opposite side panels of the front wall 38 may be moved toward opposite side edges thereof to open the slit to its fullest extent and permit the insertion of a garment into the garment bag and the suspension of said garment on a hanger 52 the hook of which is engaged over the loop 50. With the garment thus positioned within the bag, the slide fastener 48 is moved upwardly to close the slit 42 and the garment will be thoroughly protected against the collection of dust and dirt.

While in the foregoing there has been shown and described the preferred embodiment of this invention it is to be understood that minor

changes in the details of construction, combination and arrangement of parts may be resorted to without departing from the spirit and scope of the invention as claimed.

5 What is claimed is:

A clothes bag holder comprising an elongated substantially transversely inverted U-shaped hood, a spring actuated roller carried by the hood within the confines thereof, a coiled spring about 10 said roller connected at one end to said hood and at the other end to said roller urging said roller in rotation in one direction, an elongated bar carried by the roller in spaced relation thereto, an elongated hanger member for said bag holder fastened at the opposite ends thereof to the opposite ends of said hood, a clothes bag of flexible material having a front wall, a back wall and gussets connecting the side and bottom edges of the front and back walls, means adjacent the upper edge of the back wall permanently connecting the back wall to the roller diametrically opposite the rod, the front wall having a vertically extending elongated slit extending therethrough, said slit opening through the upper edge of the front wall substantially midway between opposite ends thereof, a slide fastener carried by the front wall for closing said slit, means carried by the front wall adjacent the upper end thereof on opposite sides of the slit and engaging the rod to support the front wall for sliding movement longitudinally of the rod, a notched drum carried by the roller without the hood, a spring actuated pawl carried by the hood for entering a notch and holding the roller against movement under the influence of the spring, and a relatively shallow loop carried by the roller midway between opposite ends thereof for receiving the supporting hook of a garment hanger.
